The ornamental design for a rechargeable motor oil filter holder, as shown and described.

DESCRIPTION

FIG. 1 is a top perspective view of a rechargeable motor oil filter holder showing my new design;
FIG. 2 is a side elevational view thereof, drawn to a slightly reduced scale, the opposite side elevational view being a mirror image thereof;
FIG. 3 is a top plan view thereof; and,
FIG. 4 is a bottom plan view thereof.

FIG.1

FIG.2

FIG.3

FIG.4
